UNITED STATES PATENT OFFICE

2,191,018

ROLLER SKATE BRAKE

Anthony Ickenroth, Brentwood, Mo.

Application October 1, 1937, Serial No. 166,741

2 Claims. (Cl. 280—11.20)

This invention relates to improvements in roller skates and has for its object to provide an automatic brake for the skates.

Another object of the invention is to provide an automatic brake for a roller skate the action of which is controlled by the movement of the foot of the user.

Another object of the invention is to provide a brake so constructed that it may be attached 10 to any ordinary roller skate.

A further object of the invention is to provide a brake for a roller skate so arranged that upon raising the toe of the skate the brake is automatically applied.

15 A still further object of the invention is to provide a brake for a roller skate so arranged that the tension of the brake may be controlled by the user, in order that he may go full speed, slow down, or stop altogether, as desired.

20 A further and principal object of the invention is to provide a roller skate so formed that its movement may be fully controlled by the user at all times, thus providing such a skate which can be used by even a novice in perfect safety.

25 With the above and such other objects in view, as may hereinafter more fully appear, I have invented the device shown in the accompanying drawing, in which:

Figure 1 is a side elevational view of a roller 30 skate, in normal position, embracing my invention, and partly broken away;

Figure 2 is a similar view, showing the brake applied;

Figure 3 is a rear elevational view of Figure 1;

35 Figure 4 is a section on line 4—4 of Figure 1;

Figure 5 is a perspective view of my brake, shown removed from the skate; and

Figure 6 is a detail perspective view of a brake shoe.

40 Like reference characters indicate like parts throughout the following specification, and in the several views in the drawing, in which 1 indicates a roller skate of usual construction, and to which is attached my improved brake 2. This 45 brake consists of a nickel frame 3, having side walls 4 and 5, and a rear wall 6. The rear portions 7 and 8 of the walls 4 and 5, and the rear wall 6, project downwardly on an incline and form a housing for a solid soft rubber brake shoe 9, which is so pivoted between the walls 7 and 8 by a bolt 10 that the lower wall portion 11 projects about one-fourth of an inch below the lower edges 12, 13 and 14 of walls 6, 7 and 8.

The walls 4 and 5 form arms which are adapted 55 to project on each side of the bracket member 15,

of the skate 1, which carries the boxing 16 for the rear wheels of the skate. Provided in the forward ends 17 and 18 of walls 4 and 5, are slots 19 and 20 inclined to conform to the inclination of the forward edges of the members 15 and 15', 5 and adapted to receive a flat cotter pin 21, by means of which the brake member 2 is held in position upon the skate. The upper edges 22, 23, and 24 of said walls 4 and 5, are adapted to seat up against the plate of the skate and the projections 26 and 27 from said walls are adapted to seat under the rear axle 28 of the skate, thus the brake frame is held in rigid position. Now, normally, the brake shoe, which is pivotally held to the walls 4 and 5, by a pin 29, is held about three-eighths of an inch above the skating surface, however, when the skater raises the toe of the 10 skate the brake shoe 9 drops to engagement with said skating surface, or floor, the greater the angle to which the toe of the skate is raised, the greater the pressure of the brake, therefore, the skater may readily slow up speed or stop altogether, as he may desire.

The brake shoe is preferably triangular in cross section, and its corners 30, 31, and 32 are slightly 15 rounded, consequently, when the lower wall 33 of the brake, engages the floor or other skating surface, the brake shoe has the action of a cam, its forward corner 34 dropping below the rest of 20 said lower portion and effectively braking the 30 speed of the skate. The pin 29 may be withdrawn and the brake shoe turned to let one of its other surfaces 35 or 36 come into braking position when the first wall 33 becomes too worn for effective action.

Having now described my invention, that which I claim to be new, and desire to procure by Letters Patent is:

1. In a device of the class described, in combination with a roller skate having a frame and a rear wheel, a bracket member supporting the wheel, said wheel having an axle, a frame substantially U-shaped in contour having side walls and a rear wall, said side walls straddling the bracket member, said side walls having projections engaging about the end portions of the axle for retaining the frame in operative position about the rear of the skate, a brake shoe carried by the frame, means pivotally mounting the brake shoe in the frame, said means extending through 40 said shoe and through the side walls of the frame, and means carried by and extending through the forward portions of the side walls and engaging the bracket for retaining the frame in operative 45 position, the skate and frame being tiltable for 50 said shoe and through the side walls of the frame, and means carried by and extending through the forward portions of the side walls and engaging the bracket for retaining the frame in operative 55 position, the skate and frame being tiltable for 55

engaging the brake shoe with a surface over which the skate is traveling for permitting arresting of forward movement of the skate.

5. 2. In a roller skate brake, a sheet metal frame bent to U-shape and adapted to be positioned in straddling relation with the rear wheel bracket of a roller skate, said frame having a flat bight portion, a braking shoe carried by the frame at

the rear thereof in parallel relation with the bight portion, and a cotter key connecting the arms of the frame at their corresponding forward ends and retaining the frame and brake shoe in operative position on the skate, said cotter key being removable for freeing the frame and brake from the skate.

ANTHONY ICKENROTH.
